UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

LEDGER SHEET.

Application filed June 20, 1921. Serial No. 478,799.

To all whom it may concern:

Be it known that I, JESSE A. B. SMITH, a citizen of the United States, residing in Stamford, in the county of Fairfield and 5 State of Connecticut, have invented certain new and useful Improvements in Ledger Sheets, of which the following is a specification.

This invention relates to bookkeeping and 10 is herein illustrated in connection with an Underwood standard typewriter carriage, which may form part of an Underwood standard bookkeeping machine.

This application is a division of my co- 15 pending application, Serial No. 301,034, filed May 31, 1919, now Patent No. 1,386,375 dated August 2, 1921.

In using such bookkeeping and other printing computing machines, when it is de- 20 sired to record both items and balances, it frequently becomes necessary to write what is called a "pick-up" balance in order to be able to compute a new balance by adding an item to the old balance. In some kinds of 25 bookkeeping, such as bank-bookkeeping, the work-sheet is very wide even if it contains no "pick-up" balance column, with the result that it becomes unmanageable in a typewriter-carriage, if additional columns are 30 provided for the "pick-up" balance in addition to the column already needed upon the sheet.

According to the present invention, it is 35 unnecessary to provide such columns upon the sheet itself. To render such columns unnecessary upon the sheet, there may be provided a strip which is held in position in the typewriter-carriage, and which, upon the insertion of the work-sheet, overlies some 40 column which it is not desired to use at the moment, thus permitting any "pick-up" balance to be written upon said strip. Inasmuch as the work-sheet herein illustrated is a "Boston" ledger-sheet containing on one 45 face a separate column for each day of the week, the strip may be in the form of what is commonly called a tally-strip, and may be drawn from a tally-strip-roll or holder which is adapted to be located at various 50 positions along the carriage, depending on the day column in use. To facilitate the easy and accurate locating of the tally-strip-roll, the reel or holder from which it is drawn may be mounted upon a part which

extends the length of the typewriter-carriage and which is adapted to retain the reel at any column to which it has been positioned.

Other features and advantages will hereinafter appear.

In the accompanying drawings,

Figure 1 is a diagrammatic perspective view of an Underwood typewriter-carriage and work-sheet comprising the present invention.

Figure 2 is a sectional side view of the same.

Figure 3 is a fragmentary view of a work-sheet and a strip thereupon as used for making two entries.

The work-sheet 10 is inserted around the platen 11 by passing it between the platen and the reel 12, so that it comes between the platen and the strip 13, and is guided by the usual rear paper-table 14 to the rear feed-rolls 15, and thence to the front feed-rolls 16 which carry the work-sheet around to the front of the platen so that it swings up to the printing line at the usual wing-scale 17. The work-sheet 10 is shown as a "Boston" ledger-sheet including the name column 18 and line-number column 19 and a series of day columns 20, one for each day of the week. Each day column 20 comprises a checks column 21, a deposits column 22, and a daily 70 balance column 23, the latter column serving to show at the last entry beside any name the current working balance of that account.

If the depositor Doe at line 1 (Figure 3) has a working balance of \$250.75, and a check or checks amounting to \$75.00 come to the typist's desk to be charged against said balance, the typist, preliminarily to making the entry, sets the typewriter-carriage so that the typewriter-types 24 will print through the usual ribbon (not shown) upon the strip 13, which overlies the checks column 21 of Tuesday, and copies upon said strip the amount \$250.75 shown as the first item upon said strip in Figure 3. This copying, in the usual manner, adds that item in the usual computation-register of the Underwood bookkeeping machine, one form of which is shown in the patent to Hoyt, No. 1,280,228, dated October 1, 1918. Then the typist brings the typewriter-carriage so that the types 24 will write in the checks column 21 of Monday, and writes therein the item

\$75.00, subtracting it at the same time from the computing register, and usually simultaneously adding it into the usual checks register of the machine. Then the typist 5 sets the typewriter-carriage so that the types 24 will write in the Monday daily balance column 23, and copies therein the amount \$175.75, now shown in the computing register, subtracting it from that register and 10 thereby bringing that register to zero. Then the typist prints the usual star 25 to prove the accuracy of the copying.

If the deposits item \$125.50 comes to the 15 typist's desk at the same time as the checks item, preliminarily to entering the deposit, the typist copies the new daily balance \$175.75 upon the strip 13 from the daily balance column 23, and adds it into the computing register. Then the typist sets 20 the typewriter-carriage so that the types 24 will write in the deposits column 22, and writes therein the item \$125.50, adding it in the computing register, and also adding it in the usual deposits register of said machine. Then the typist sets the typewriter-carriage so that the types will print in the daily balance column 23, and writes therein the balance now shown in the computing register, viz., \$301.25, subtracting it 25 from that register, and then printing the usual star to prove the accuracy of the copying. If this is the last item to be entered at this time upon said work-sheet 30 10, it may be removed from the machine, either by advancing the platen or by casting off the feed-rolls by the usual handle 26, which is connected by the usual link 28 to the usual feed-roll-release-shaft 29.

If the work-sheet is removed as by casting off the feed-rolls and withdrawing it, 40 the typist may detach the written-on portion of the strip 13 and discard it. Upon the insertion of a new work-sheet, the advance of the work-sheet to the printing line 45 carries around with it the strip 13, thus bringing a fresh portion of the strip to the printing line to serve for receiving the new "pick-up" balances.

To insure sufficient supply of the strip 50 13, it is preferably furnished in the form of a roll 30, which may be mounted on the reel or spool 12, said reel being journaled upon the shaft 32, which is mounted upon brackets 33 fast to the cover-plates 34 of the typewriter-carriage. The reel 12 may 55 comprise side plates 35 and 36, which turn with the hub 37, the latter journaled upon the rod or shaft 32.

In order to accurately and rapidly position the hub 37 axially of the shaft 32, there 60 is provided in the extension 38 of the hub a spring-detent 39, which is adapted to seat itself in a channel 40 extending circumferentially of the rod 32, thereby permitting 65 the reel 12 to turn with some friction while

preserving its alignment relatively to the inserted work-sheet. In order that the work-sheet 10 may be accurately adjusted longitudinally of the platen, there is provided one or more side gages 41.

70

To remove the reel 12 from the rod 32, or to permit a new strip-supply-spool 30 to be inserted, the rod 32 may be held in place in one bracket 33 by means of a thumb-screw 48, which is threaded in the 75 post 49 and adapted to enter a depression in the rod and hold it against slipping.

75

Since it is desired to position the strip 13 at a different point for every day, the rod 32 is provided with a series of channels 80 40 spaced at distances corresponding to the day columns 20 upon the work-sheet, including a channel to hold the strip 13 over the transfer column 51 on Saturday, when Saturday's "pick-up" items are written on 85 the strip. Then the strip may be removed, and the items in the main Saturday column may be copied in the transfer column 51, according to the custom. The usual fold is then made, which brings this transfer column alongside of the Monday column which 90 is printed as usual on the other side of the sheet.

90

For advancing the work-sheet, the usual line-space mechanism, which includes the line-space wheel 52, may be used, or the usual knob 53 may be used. In order to enable the strip 13 to be advanced by the feed-rolls in all its positions, the feed-rolls are extended so as to come up almost to the usual arms 54 by which their shafts 55 are carried, thus making the structure such that there will always be feed-rolls to engage the strip 13 wherever the strip 13 is positioned.

95

Variations may be resorted to within the scope of the invention, and portions of the improvements may be used without others.

Having thus described my invention, I 100 claim:

105

1. The combination with a "Boston" ledger-sheet having day columns, each including subsidiary columns for transactions and daily balances, of means to enable the use of said sheet in a combined typewriting and computing machine in which computation of a transaction for any day involves the typing of the previous balance and the running of the same into the register, without the provision on the ledger-sheet of a separate "pick-up" column for each day in which to type the previous balances, said means comprising a temporary pick-up strip of suitable width, usable for each of a plurality of days, whereby, in picking up a previous balance preparatory to entering a debit or credit item for the day, the previous balance may be typed on said temporary "pick-up" strip placed in a suitable position overlying said ledger-sheet.

110

115

120

125

130

2. The combination with a "Boston" ledger-sheet, for use in a combined typewriting and computing machine in which computation of a transaction for any day 5 involves the typing of the previous balance and the running of the same into the register, said ledger-sheet having day columns, each including subsidiary columns for transactions and daily balances, and a "pick-up" 10 transfer column at the right of the last day column of the ledger-sheet, of means to enable the use of said sheet in the machine without the provision thereon of separate "pick- up" columns for each of the other days, 15 said means comprising a temporary "pick-up" strip of suitable width, usable for each of a plurality of days and supportable at different suitable positions on said sheet, whereby, in picking up a previous balance preparatory to entering a debit or credit 20 item for any day, the previous balance may be typed on said temporary "pick-up" strip.
